UNITED STATES PATENT OFFICE.

ROMEO POZZI, OF MARYSVILLE, CALIFORNIA.

CUTTER FOR BUTTER, &c.

SPECIFICATION forming part of Letters Patent No. 770,476, dated September 20, 1904.

Application filed June 30, 1904. Serial No. 214,828. (No model.)

To all whom it may concern:

Be it known that I, ROMEO POZZI, a citizen of the United States, residing at Marysville, in the county of Yuba and State of California, have invented new and useful Improvements in Cutters for Butter and Like Articles, of which the following is a specification.

My invention relates to a device which is designed for cutting butter, bread, or any article which it may be desired to cut into slices of regular thickness.

It consists in the combination of mechanism and devices by which the article to be cut is intermittently advanced between the movements of the cutting device and means by which the rate of advance and the thickness of the slices cut may be varied.

It also comprises details of construction which will be more fully explained by reference to the accompanying drawings, in which—

Figure 1 is a plan view of my invention. Fig. 2 is an end view of same, showing cross-wires. Fig. 3 is a transverse section showing rack and plunger.

The device shown in the drawings is especially designed for cutting butter from the block or roll into sheets of any desired thickness and subdividing said sheets to make the smaller divisions or parts designed for table use.

A represents a box made of any suitable material and of a size to receive the block, roll, or loaf, if it is used for cutting bread, which is placed within the box.

2 is a plunger fitting said box and adapted to move lengthwise thereof.

The box is here shown as having two sides and a bottom, and the plunger fits sufficiently closely between these sides and the bottom.

The top of the device may be open, as shown. Through the rear end of the box extends a rack-bar 3, having at the front end a plate 4 or equivalent means, by which it is fixed to the plunger, so that the latter stands transversely

45 of the box and it may be advanced by the movements of the rack-bar. Transversely across the box is a shaft 5, having a pinion 6, which engages with the rack-bar. In the present case this shaft and pinion are located

50 below the rack-bar, and a bar 7, extending

across the box above the rack-bar, maintains the teeth of said bar in constant mesh with the pinion. Upon the outer end of the transverse shaft is fixed a bevel gear-wheel 8. Parallel with the side of the box is journaled a shaft 55 9, having a pinion 10, which engages with the gear 8, as shown. This pinion has a portion of its teeth cut out, so as to form a mutilated pinion, and it will be manifest that when its teeth engage those of the gear-wheel the latter will be revolved, and through the shaft and interior pinion engaging with the rack-bar said bar and the plunger carried by it will be advanced. During the time when no pinion-teeth engage with the gear-wheel the plunger and the butter or other substance which lies in front of it and is moved by it will remain stationary. During this stationary period the cutter is brought into action and a slice of the material is cut off. In the present 70 case the shaft 9 is bent or has fixed to it an arm, as shown at 11, and this arm is again bent upon itself, as shown at 12, so that between this bent arm and the journal portion of the shaft a cutter 13 is fixed. A handle 14 75 is fixed to the arm 11, and by this handle the shaft may be revolved and the mechanism operated. The position of the arm and the cutter is so arranged with relation to the mutilated pinion that when the latter ceases to advance the gear the cutter will be in position to commence the cut upon the normally stationary substance and it will pass across the open end or mouth of the box A before the pinion again engages the gear. Thus the material will be cut into slices of a given thickness and may drop from the end of the box into a suitable receptacle below.

If bread is to be cut by this device, a suitably-constructed sharp knife will form the 90 cutter 13, and the bread will be advanced at each revolution of the crank-shaft and connected parts a distance sufficient to make slices of the desired thickness. If butter is to be cut, it is usually desirable to also cut 95 the butter into small sections or pats, such as are usually placed upon butter-plates for table use. For this purpose I have shown the cutter in the form of a thin wire stretched between the shaft and the part 12 for the 100

purpose of cutting the butter into slices, and across the mouth of the box are stretched flat wires, as at 16, so that as the butter is advanced by the plunger 2 it will be forced across these 5 wires 16, thus subdividing into small sections, after which the main cutter-blade 13 will sever these cut sections from the end of the block or roll. A pan containing water may be conveniently placed to receive these 10 sections as they fall from the apparatus.

In order to vary the thickness of the slices which are to be cut, I employ a series of pinions 10, which are fitted upon the end of the shaft 9, so that they may be easily removed. 15 If a thin slice of material is to be cut, a pinion with a considerable number of teeth cut out may be employed for the purpose. If a thicker slice is to be cut, more teeth will remain in the pinion, and the consequent result 20 will be a greater revolution of the gear and a further advance of the rack-bar and the plunger which is moved thereby. The proportionate size of the gear and pinions may be adjusted to suit the character of the work to 25 be done.

Having thus described my invention, what I claim, and desire to secure by Letters Patent, is—

1. A device for slicing material consisting 30 of a box or guide therefor, a plunger having a guided rack-bar attached thereto and movable within the box, a transverse shaft with a pinion engaging the rack-bar, said shaft having a bevel gear-wheel upon its outer end, a 35 shaft journaled parallel with the side of the box, a mutilated pinion fixed to said shaft to engage the gear-wheel and advance it and the connected parts intermittently, a cutter car-

ried by said pinion-shaft movable across the front of the box through which the material 40 is advanced, said cutter being fixed to sever the material during intervals in its advance.

2. In a device for slicing material, a containing-box, a plunger having a guided rack-bar fixed to it and movable to advance the 45 material through the open end of the box, a transverse shaft with pinion engaging the rack-bar, a bevel-gear fixed to the outer end of said shaft, a second shaft journaled parallel with the side of the box, a pinion removably 50 secured upon the last-named journal-shaft, a crank-arm fixed at right angles with said shaft and coinciding with the mutilated portions of the pinion whereby it crosses the open mouth of the box while the advance of the material 55 is arrested and a cutter carried by said arm.

3. In a device for cutting material, a containing-box open at one end adapted to receive the material, a plunger rack-bar, pinion and mutilated gears by which the material is 60 intermittently advanced through the mouth of the box, cutters transversely disposed across the mouth of the box whereby the block of material is subdivided into smaller sections, and a cutter connected with the mutilated-pinion shaft and movable across the end of the box to sever the material projecting therefrom during the intermission of its forward movement.

In testimony whereof I have hereunto set 70 my hand in presence of two subscribing witnesses.

ROMEO POZZI.
